(57) **CLAIM**

The ornamental design for a chicken coop heater, as shown and described.

DESCRIPTION

FIG. 1 is a front, left and top perspective view of a chicken coop heater showing my new design;

FIG. 2 is a rear, right and bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a perspective view thereof, showing the chicken coop heater in an alternate position; and,

FIG. 10 is another perspective view thereof.

The broken lines illustrate portions of the article that form no part of the claimed design.
